ATTORNEY

UNITED STATES PATENT OFFICE.

MILNER H. BATES, OF SOUTH CHICAGO, ILLINOIS.

BOTTLE-HOLDER.

1,264,754.

Specification of Letters Patent.

Patented Apr. 30, 1918.

Application filed December 28, 1915. Serial No. 69,086.

To all whom it may concern:

Be it known that I, MILNER H. BATES, a citizen of the United States, residing at South Chicago, in the county of Cook and State of Illinois, have invented certain new and useful Improvements in Bottle-Holders, of which the following is a specification.

My invention relates to a novel construction of bottle holder and has for its primary object to provide a device of this class which may be placed in a convenient position to receive milk, bread or other articles which are usually delivered in the early hours of the morning, and to retain the same against theft.

Another object of the invention is to provide a device wherein the weight of a milk bottle or other article placed thereon actuates a tripping device, which permits a sliding door to be closed and held in locked relation by the receptacle.

A further object is to provide a device of this class which will be comparatively inexpensive to produce, and which will be substantial in construction and simple in operation.

With these and other objects in view, the invention consists in the construction and operation of the various parts as will be hereinafter described and claimed.

In the drawings:

Figure 1 is a front elevation of the device with the door closed and in locked relation to a receptacle.

Fig. 2 is a vertical section on the line 2—2 of Fig. 1, looking in the direction of the arrow, and showing the door in open position.

Fig. 3 is a vertical section on the line 3—3 of Fig. 2 looking in the direction of the arrow.

Fig. 4 is a detail view of the lock and its protecting cover.

Referring to the drawings, 1 denotes a metallic receptacle having a door 2 adapted to slide in the grooves 2' and 2'', formed at the top 3 and the bottom 4 of the receptacle. Apertures 5 are provided in the rear wall 6 through which screws or other suitable means may be passed to secure the device to a door frame or other support.

Hingedly secured at 7 to the bottom 4 of the receptacle is a tripping member 8 having coil springs 9 disposed between the front edges thereof and the bottom of the recep-

tacle. A rod 10 adapted to reciprocate vertically is pivotally connected to the tripping member 8 adjacent the side wall of the receptacle, and has an upper end adapted to pass through an aperture 10' in the top of the receptacle. The rod 10 is further provided with the forwardly extending arms 12 and 13 which are secured to the side wall of the receptacle by means of retaining brackets 12' and 13'. The ends 14 and 15 of the arms 12 and 13 are adapted to engage lugs 16 and 17 carried by the door 2.

Secured to the side of the receptacle at the top and bottom thereof by eyes 18 and 19 are coil springs 20 and 21 having their opposite ends secured by means of the eyes 22 and 23 to the door 1. The coil springs 20 and 21 are adapted to pass through apertures 24 and 25 in the side of the receptacle 1 when the door 2 is in an open position.

The door 2 is provided with a handle 26 and a spring lock 27 adapted to enter an aperture 28 in the side of the receptacle 1 and be secured thereto. A cover 29 is adapted to cover the aperture 28 and to be riveted to the side of the receptacle 1. A key-hole 30 designed to receive a key is provided in the lock 27.

In operation the door 2 is adapted to be held in open position against the tension of the coil springs 20 and 21, through the medium of the arms 12 and 13 and their retaining brackets 12' and 13'. The outer ends 14 and 15 of the arms 12 and 13 engage the lugs 16 and 17 carried by the door 2. When a bottle of milk or other article is placed on the tripping member 8, it is evident that the weight thereof will overcome the resistance of the coil springs 9, and depress the tripping member 8 thereby pulling down the rod 10 and disengaging the ends 14 and 15 of the arms 12 and 13 from the lugs 16 and 17 of the door 2. The door will then be instantaneously closed by the action of the springs 20 and 21. When the door 2 is closed by the action of the coil springs 20 and 21 a spring lock 27 carried thereby will engage an aperture 28, and be held in locked engagement thereby, until the same is unlocked by a key in the hands of the owner of the device. The bolt 27' of the lock is provided with movable side wings 27' for engaging the sides of the receptacle adjacent the aperture 28. This is the well known form of lock and forms no part of my in-

vention. The door is then pulled back and the contents removed allowing the tripping member 8 to return to its normal raised position, thereby lifting the forwardly extending arms 12 and 13 into engagement with the lugs 16 and 17 of the door 2.

It is to be understood that I do not limit means to the exact construction shown herein, but reserve the right to make such changes and alterations as do not depart from the spirit and scope of the appended claims.

I claim:

1. A bottle receiving receptacle comprising a door, spring means for normally holding the same closed, a trip arm engaging a part of the door to hold the same fully open against the spring tension and means for tripping said arm when a bottle is placed in the receptacle.
2. A bottle receiving receptacle comprising a door, spring means for normally holding the same closed, a trip arm engaging a part of the door to hold the same fully open against the spring tension and a spring controlled platform for tripping said arm when a bottle is placed thereon.
3. A bottle receiving receptacle comprising a door, spring means for normally holding the same closed, a trip arm engaging a part of the door to hold the same fully open against the spring tension, a spring controlled platform and a member pivoted to said platform and engaging the arm for tripping the same when a bottle is placed upon the platform.
4. A bottle receiving receptacle comprising a sliding door, springs securing the door to the receptacle to normally hold the same closed, a rod having arms thereon engaging with a part of the door to hold the same fully open against the spring tension, means for guiding the arms so as to permit vertical movement of the rod and arms and a spring controlled platform pivoted to the rod for

releasing the arms from the door when a 45 bottle is placed thereon.

5. A bottle holder including a receptacle, a door slidably associated therewith for closing the same, closing means carried within the receptacle and secured to the receptacle 50 and to the door for normally closing the door, holding means carried within the receptacle to hold the door in open position, means carried by the door for engaging the holding means, spring held tripping means 55 adapted to receive an article to be placed in the receptacle, pivotally connected to the holding means and hingedly connected to the receptacle to trip the holding means, locking means carried by the door and means 60 carried by the receptacle for engaging the locking means to hold the door in locked relation with the receptacle.

6. A bottle holder including a metallic receptacle, a door associated therewith for 65 closing the same, grooves formed as a part of the receptacle to hold the door in sliding engagement therewith, coil springs connected between the receptacle and the door to normally close the same, a vertical reciprocating rod, forwardly extending holding arms on the vertical rod, retaining brackets associated with the holding arms and carried by the receptacle, lugs on the door for engaging the holding arms, and a spring 75 held tripping member pivotally connected to the vertical rod and hingedly connected to the receptacle adapted to receive an article to be placed in the receptacle, whereby the tripping member is operated to reciprocate the vertical rod and move the holding arms out of engagement with the door.

In testimony whereof I affix my signature in presence of two witnesses.

MILNER H. BATES.
